UNITED STATES PATENT OFFICE

VASCO PINI, OF NEW YORK, N. Y.

ATTACHMENT FOR PROJECTORS.

1,186,495.

Specification of Letters Patent.

Patented June 6, 1916.

Application filed July 28, 1915. Serial No. 42,275.

To all whom it may concern:

Be it known that I, VASCO PINI, a subject of the King of Italy, and a resident of New York, in the borough of Brooklyn, county 5 of Kings, and State of New York, have invented certain new and useful Improvements in Attachments for Projectors, of which the following is a specification.

My invention relates to kinetoscopes, and 10 the main object thereof is to provide an attachment for the projecting head whereby various color effects may be thrown upon the screen with untinted films in order to enhance the effect, to accomplish the same 15 results produced with tinted films, and to improve on the latter by differently tinting the projection at different positions on the screen as, for instance, tinting the sky blue or yellow, and the ground or water green.

20 My invention is fully described in the following specification, of which the accompanying drawings form a part, in which like characters refer to like parts in each of the views, and in which:—

25 Figure 1 is a fragmentary side view of a kinetoscope with my attachment in operative position thereon; Fig. 2 is an enlarged side view of the attachment; Fig. 3 is a detached face view of a screen frame which I 30 employ, partially open; Fig. 4 is an enlarged section taken on the line 4—4 of Fig. 5; Fig. 5 is a view similar to Fig. 3 but in closed position, and showing the two-color screen therein, in one adaptation 35 thereof; and Fig. 6 is a section taken on the line 6—6 of Fig. 2.

In Fig. 1 of the drawings forming a part 40 of this application, I have shown fragmentarily the lamp-box 7 and the projecting head 8 of a kinetoscope, the film 9 and window 10 being shown in the latter, and in the practice of my invention I prefer to arrange the same between said lamp and window as shown, but I do not confine myself 45 to such arrangement.

The invention consists of a bracket 11 secured to the head 8 and carrying an upper horizontally arranged bar 12 and a lower horizontal bar 13, the former of which 50 serves as the pivotal point for a plurality of levers 14 in pivotal connection with the respective ones of a corresponding number of slide bars 15 movable in the latter bar 13, and the bar 12 also carries an arm 16 55 which serves as a bearing for a push-rod 17

for each of the levers 14, as is clearly shown in Fig. 2.

The levers 14 are preferably linked to the respective slide-bars and each of said slide-bars carries a dependent bar 18 which serves 60 as a support for two forwardly directed parallel rods 19 and 20, and each of said slide-bars also carries two stops 21 and 22 which serve to limit the movement thereof in the corresponding directions. If one of 65 the push-rods 17 is manually forced inwardly from normal outward position, the corresponding lever 14 is swung on its pivot 23 to move the respective slide-bar 15 forwardly out of normal rearward position, 70 one unit being shown in forward position at X in Fig. 2 and one in rearward position at X².

Each of the slide-bars 15 carries a detachable frame 24 containing a color screen 25, 75 either entirely of one color or party-color, said frames having, each, two hooks 26 on the upper edge thereof and one hook 27 at the lower edge thereof detachably engaged, respectively, with the parallel rods 80 19 and 20, the natural spring of these rods permitting the ready connection of the frame therewith or disconnection therefrom.

Each frame 24 is preferably composed of 85 two members 28 and 29, as shown in Figs. 3, 4, and 5, the hooks 26 and 27 being formed integrally on the member 28 which also carries three integral clamps 30 engaging the member 29 and the member 29 carries similar clamps 31 to engage the member 28, only one of said clamps 31 being shown, in Fig. 4. These members are slid one over the other for connection and disconnection, and the color screen 25 is arranged therebetween, being held by the spring tension of the clamps in a readily removable manner.

The normal rearward positions of the 100 color screens is out of the path of the rays of light from the lamp-box to and through the projector head, and the forward position of a screen is directly in the path of the light; when one of the push-rods 17 is 105 forced rearwardly from normal position X², the respective color screen 25 is forced forwardly into the position X into the path of light, and the rays of light are correspondingly tinted, either single or party- 110 color according to the form of the screen,

and the projection on the screen through an untinted film is correspondingly tinted. This instantly produces the very desirable effects now accomplished by tinting the film 5 itself, either entirely of one color, or different sections or scenes of different colors, so as to produce sun, sea, storm, night, or other effects, but one of the results possible to my invention is in the ability to produce 10 different tint effects during the same scene as, for instance, bright sunlight on one side of the screen and a fire on the other side of the surface thereof, and these party-color effects are multitudinous and greatly enhance 15 the light values of the projection.

While I have shown a very simple, efficient, and satisfactory structure, it will be obvious that many changes may be made thereover, and I reserve the right to all 20 such changes as come within the scope of the following claims.

Having fully described my invention, what I claim as new, and desire to secure by Letters Patent, is:—

25 1. The combination with a kinetoscope, of an attachment comprising a support, a plurality of slide-bars carried thereby, two parallel rods carried by each slide-bar, a frame in detachable connection with each slide-bar comprising two members provided 30

with spring clamping members each adapted to engage the other, hooks on one member for engagement with the said parallel rods, a color screen held between said members, and means for actuating each slide-bar to move the respective color screen into and out of the path of light.

2. The combination with a kinetoscope, of an attachment comprising a support, a plurality of slide-bars carried thereby, two 40 parallel rods carried by each slide-bar, a frame in detachable connection with each slide-bar comprising two members provided with spring clamping members adapted, each, to engage the other, hooks on one member for engagement with the said parallel rods, a color screen held between said members, and means for actuating each slide-bar to move the respective color screen into and out of the path of light, said screen 45 being divided into a plurality of colorably distinguishable sections.

In testimony whereof I have signed my name to this specification in the presence of two subscribing witnesses.

VASCO PINI.
